(57) **CLAIM**

I claim the ornamental design for a data cable component, as shown and described.

DESCRIPTION

FIG. 1 is a perspective view of a data cable component showing my new design.

FIG. 2 is a second perspective view of FIG. 1, viewed in another aspect.

FIG. 3 is a front view thereof.

FIG. 4 is a back view thereof.

FIG. 5 is a left view thereof.

FIG. 6 is a right view thereof.

FIG. 7 is a top view thereof.

FIG. 8 is a bottom view thereof.

FIG. 9 is a perspective reference view thereof in an environment in which it may be used; and,

FIG. 10 is another perspective reference view thereof in an environment in which it may be used.

The broken lines in the drawings depict portions of the data cable component that form no part of the claimed design.
